(57) **CLAIM**

I claim the ornamental design for a $13/16$ -inch-spark-plug-socket hot rod wrench, as shown and described.

DESCRIPTION

FIG. 1 of the drawings is a perspective view showing the front, right side, and top of a $13/16$ -inch-spark-plug-socket hot rod wrench embodying the design of my invention;

FIG. 2 is another perspective view showing the back, bottom, and left side of the hot rod wrench;

FIG. 3 is a right side elevation view; and,

FIG. 4 is a top plan view.
